UNITED STATES PATENT OFFICE

OWEN A. McNAMEE, OF WORCESTER, MASSACHUSETTS

SAFETY APPARATUS

Application filed September 28, 1931. Serial No. 565,689.

This is an invention for a safety apparatus for motor driven rolls, it being the intention of the inventor to provide a means for warning the operator of a set of rolls when he is in a dangerous position, and to stop the rolls immediately upon giving the warning.

A characteristic feature of the invention is the use of a number of electric conductors adjacent the rolls to be protected and charged with high tension electricity, whereby the operator of the rolls will be warned by a slight shock of his dangerous position, an electric system being arranged to stop the motion of the rolls the moment these conductors are grounded.

Such an apparatus applied to a pair of rubber warming and mixing rolls is shown by the accompanying drawing. In the operation of these rolls the operator stands on a concrete floor in front of them and, as a rule, braces himself against their metallic framework. When in this position he is well grounded electrically so that if he touches the conductors, by coming in too close proximity to the rolls, he will complete the high tension circuit and will receive a slight shock which will warn him of his dangerous position. The completion of this circuit will immediately stop the rolls, to further insure the prevention of an accident.

In the drawing:

Figure 1 is a front elevation of one form of this invention.

Figure 2 is an end elevation of Figure 1.

Figure 3 is an example of an electric circuit which may be used to stop the rolls when driven by an electric motor.

Having reference to this drawing, there is shown a pair of rubber warming and mixing rolls 2 mounted in a metallic frame 3 for rotation by an electric motor 4 through a gear reduction box 5. An overhead support 6, insulatingly carried by a standard 7, extends along these rolls. A number of levers 8 are pivotally carried by the support 6 at spaced intervals and themselves carry depending chains 9 and chain counterweights 10, any one of these chains being capable of raising to pass lumps of rubber

on the rolls 2 without interfering with the others. An insulated rod 12 is arranged over these levers 8 near their counterweighted ends so that the chains 9 are properly maintained in position. It is to be understood that the counterweights 10 do not quite balance the chains 9 so that the levers 8 will bear against this rod 12.

The circuit charging the chains 9 and stopping the motor 4 may consist in a 3-pole relay 13 interposed in a main line 14 which supplies current to the motor 4. A step-down transformer 15 is connected to the line 14 and normally energizes a step-up transformer 16 through a second 3-pole relay 17. This step-up transformer maintains a high voltage, low amperage grounded charge in the chains 9, the relay 17 being balanced for operation by a slight increase in current. Such an increase occurs the moment the chains 9 are grounded, the relay 17 thereupon breaking the circuit to the transformer 16 and closing it to the relay switch 13, which opens the power line 14 so that the motor 4 stops. The relay 17 also closes the circuit from the step-down transformer 15 to this relay's operating coil through a resistance 18, this resistance preventing the sudden increase in current which would necessarily occur when the resistance of the step-up transformer was removed.

When the operator of the rolls accidentally touches the chains 9 he receives a slight shock. This simultaneously causes the increase mentioned in the above paragraph so that the relay 17 breaks the circuit to the transformer 16 and closes the relay switch 13, this opening the power line 14 so that the motor 4 stops and prevents injury to the operator.

This circuit arrangement is particularly illustrative of only one method of accomplishing the desired results and need not necessarily be adhered to should some suitable substitute suggest itself.

In fact, all of the specific structures here shown and described are in accordance with the patent statute requirements, and have not been shown with the intention of limiting the scope of this invention exactly

thereto, except as is defined in the appended claims.

I claim:

1. A safety device for motor driven rolls comprising an overhead support extending along the rolls, levers pivotally carried by said support, depending electric conductors carried by said levers, counterweights on said levers for balancing said conductors and means for charging said conductors with grounded high tension electricity, said charging means delivering an electrical shock to a person in contact therewith, and simultaneously stopping said motor driven rolls.

2. A safety device for motor driven rolls comprising an overhead support extending along the rolls to be protected, levers pivotally carried by said support, electric conductors depending from said levers to points adjacent said rolls, counterbalances on said levers for balancing said conductors, means for charging said conductors with high tension electricity and means operable by the grounding of said conductors for stopping said rolls.

3. A safety device for motor driven rolls comprising an overhead support extending

along the rolls to be protected, levers pivotally carried by said support, flexible electric conductors depending from said levers to points adjacent said rolls, weights affixed to the ends of said conductors for maintaining them taut, counterbalances on said levers for balancing said weighted conductors, means for charging said conductors with high tension electricity, said charging means delivering an electrical shock to a person in contact therewith and simultaneously stopping said motor driven rolls.

4. A safety device for motor driven rolls comprising an overhead support extending along the rolls to be protected, levers pivotally carried by said support, flexible electric conductors depending from said levers to points adjacent said rolls, weights affixed to the ends of said conductors for maintaining them taut, counterbalances on said levers for balancing said weighted conductors, means for charging said conductors with grounded high tension electricity, said charging means delivering an electrical shock to a person in contact therewith and means operable by the grounding of said conductors for stopping said rolls.
